FROSTER FOR BEVERAGE GLASSES OR SIMILAR ARTICLE

Warren C. Welch, Haddonfield, N.J., assignor to San-O-Frost Corp., Moorestown, N.J., a corporation of New Jersey

Filed Apr. 6, 1965, Ser. No. 84,639

Term of patent 3½ years

(Cl. D67—2)

FIG. 2 is a top plan view thereof, the bottom being the same as the top shown except for the opening in the top.

I claim:

The ornamental design for froster for beverage glasses or similar article, as shown and described.
